UNITED STATES PATENT OFFICE.

LEMAN P. RIDER, OF PITTSBURG, PENNSYLVANIA.

BAGASSE-FURNACE.

SPECIFICATION forming part of Letters Patent No. 349,236, dated September 14, 1886.

Application filed October 12, 1883. Renewed March 6, 1886. Serial No. 194,358. (No model.) Patented in Cuba March 15, 1882.

To all whom it may concern:

Be it known that I, LEMAN P. RIDER, of Pittsburgh, in the county of Allegheny, State of Pennsylvania, have invented a new and useful Improvement in Processes of and Furnaces for Burning Bagasse; and I do hereby declare that the following is a full, clear, and exact description thereof, reference being had to the accompanying drawings, and to the letters of reference marked thereon.

In the manufacture of sugar the sugar-cane is subjected to the action of rolls for the purpose of extracting the saccharine juice therefrom, and many attempts, but with indifferent results, have been made to utilize the green cane as a fuel after being subjected to said action of the rolls.

I have found by practical experience that damp tan-bark and also that green sugar-cane, after being subjected to the action of rolls, are of more value as a fuel than the dry tan-bark or dry sugar-cane, for the reason that in the damp or green state they have many elements which greatly assist in combustion, which elements are evaporated when the tan-bark or cane is in a dry condition.

Now, my invention consists in the method of burning green cane in the condition that it comes from the rolls and in a furnace for carrying out said method, all of which will hereinafter more fully and at large appear.

To enable others skilled in the art with which my invention is most nearly connected to make and use it, I will proceed to describe its construction and operation.

In the accompanying drawings, which form part of my specification, Figure 1 is a longitudinal section of my improved furnace, showing its application to use with a steam-boiler. Fig. 2 is a cross-section of the furnace. Fig. 3 is a top view or plan.

In the accompanying drawings, *a* is the furnace, which is built of common brick lined with fire-brick, and has an interior chamber, *a'*, of about eight feet square by about two and one-half feet in height from the grate-bars *b* to the crown of the arch *c*, which forms the top of the furnace. In the arch *c* are a number of openings, *d*—preferably six or more—for admitting the cane to the furnace, each opening having an iron frame, *d'*, and lid *d''*,

whereby it may be closed tightly. The grate *b* is provided with movable bars *b'* and a shaking-lever, *b''*. It is necessary to have either a shaking-grate or movable grate-bars. I have shown an effective form of shaking-grate, such as is described and shown in Letters Patent of the United States granted me January 23, 1877, No. 186,436; July 17, 1877, No. 193,180; and July 17, 1877, No. 193,181, to which I give preference; but any efficient and practical one will do. A detailed description of them is not necessary.

In the front wall of the furnace is an opening, *e*, closed by a suitable door, *e'*, and on top between the rows of feed-openings is arranged a receptacle, *f*, for containing a supply of fuel, such as green cane or wet tan-bark. The receptacle is fitted with openings provided with sliding doors *f'* opposite to the feed-openings *d*, so that the fuel may be drawn out of the receptacle directly into the feed-openings. Each feed-opening may, however, be provided with a separate hopper, *f''*, (shown in dotted lines in Fig. 2,) for containing fuel, from which it may be forced directly into the furnace. A combustion-chamber, *g*, is located back of the fire-chamber *a'* and between it and the boiler *h*, or other point where the heat is applied. The area of the combustion-chamber in cross-section should be equal to about one-third ($\frac{1}{3}$) of the same area of the fire-chamber, its floor on about a horizontal plane, and the chord of the arch equal to the width of the fire-chamber.

The important object of the combustion-chamber is to secure compression of the gases in their passage through said chamber, and the reverberatory action of the heated walls of the chamber upon said gases while passing through it, whereby complete combustion of the gases *g* is obtained.

The horizontal floor of the combustion-chamber secures the reverberatory action of the arch and bottom of said chamber upon the passing gases. Beyond the chamber *g* is a dust and cinder trap, *h'*, which may be supplied with a cleaning-flue, which should be closed tightly by a suitable door. The chamber *g* is lined with fire-brick. The air which supports combustion is supplied through the ash-pit *i*, the front, sides, and top of the furnace being tightly closed.

In the construction of the furnace the brick in the crown of the fire and the combustion-chambers should be laid endwise, as shown in Fig. 2, to store the greatest amount of heat in the walls for reverberatory action. In this construction a non-conductor of heat should be placed between the ends of the layers of brick.

The operation of my improvement is as follows: A fire is made in the chamber a' by means of fuel inserted through the front opening, e , which is then closed by the door e' . When the fire-chamber a' has become thoroughly heated, a charge of green cane is fed from the receptacle f through the openings d in the following manner, viz: The holes d are arranged in two rows, and the cane is charged successively through diagonally-opposite openings, so that the green charge from one opening shall not fall next to and in contact with a green charge from another opening, and also that one green charge shall not be in front and in the line of draft of another green charge.

In Fig. 3, I show six charging-holes. The first charge would be made through 6, the next 25 through 2, the next through 4, the next through 3, the next through 5, and the last through 1, and so on in the same order. The green cane being fed through the top openings, and being permitted to fall vertically on the grate, assumes a conical or pyramidal shape, as shown by the dotted lines in Fig. 1, and as the successive charges fall the bases of the cones so formed extend into contact with each other. This form is peculiarly well fitted for the driving off of the vapors and gases of the green cane, as the superficial area of the several cones presents the largest possible surface of exposure to the action of the heat, and as the broad base of each cone is exposed to and rests upon the bed of hot fuel on the grate-bars, and the gases are caused to ascend through the center of the pile, while the whole superficial area of the outside is exposed to the action of the fierce flame from the more highly-heated piles. The result is an extremely rapid distillation of the gases, which are driven over the bridge - wall k and are there thoroughly mingled in the combustion-chamber with the heated air and flame from other parts of the fire-chamber and completely consumed. When the furnace is fed as described, sufficient time is given between each charge to permit each charge to pass the period of distillation and come to a highly-heated state before the charge on the opposite side of the furnace is fed in, so that the fresh gases from such charge shall not check the consumption of the previous charge. During the operation of the furnace the grate b is occasionally shaken to open up the superimposed mass of green cane for the free admission of air and incidentally to shake out the ashes.

Practical experience has demonstrated the fact that my furnace, so fed and operated, not only successfully burns the green cane completely, leaving merely a fine dust or ash and no clogging residuum or cinder, but also that a much more intense heat is generated there-

from than can possibly be obtained by the use of dry or partially dried cane, either with or without the addition of other fuel.

Through the medium of a furnace constructed as hereinbefore described, and for which Letters Patent were granted me in Cuba March 15, 1882, and said furnace fed and operated as described, I have demonstrated fully and clearly that the practical advantages of my invention consists in the utilization of a heretofore waste substance without the necessity of preliminary treatment to render it useful. I save the cost of transporting it away from the mill, which its enormous bulk has heretofore rendered necessary at a cost, in large establishments, of thousands of dollars per annum. The arch of the chamber a' causes a reverberatory action, whereby the intense heat generated by the cones which are in advanced stages of combustion is cast down upon the cones on the opposite side of the furnace which are still in the distillation stage. Thus the heat is equalized and all parts of the fire-chamber operate to secure the thorough combustion of the cane.

I do not limit myself to any particular number or arrangement of the charging-holes, except that the number and arrangement should be such as will enable the furnace to be charged as described without damping the fire therein.

Having thus described my improvement, what I claim as of my invention is—

1. The process of burning bagasse, tan-bark, or other fuel, which consists in first heating a furnace, then charging it with fuel in conical piles successively into different parts of one and the same fire-chamber, so that one fresh charge shall not fall next to or in the line of draft of another fresh charge, substantially as described.

2. The process of burning green bagasse or wet tan-bark, which consists in depositing it in a fire-chamber alternately through diagonally-opposite openings in the crown of the furnace in conical piles, conducting air through the bases of said piles, and subjecting their surfaces to the reverberatory action of the heated walls of the furnace, substantially as set forth.

3. The process of burning green bagasse or wet tan-bark, which consists in heating a furnace to glowing heat, then charging the fuel into the fire-chamber alternately through diagonally-opposite openings in the crown of the furnace in conical piles with their bases resting upon a bed of hot fuel, substantially as described.

4. A furnace having a series of charging-holes in the crown, arranged in parallel rows over one and the same fire-chamber, substantially as described.

5. A furnace having a shaking-grate or movable grate-bars and a series of charging-holes in the crown, arranged in parallel rows over one and the same fire-chamber, substantially as described.

6. A furnace provided with a suitable grate, a series of charging-holes in the crown, arranged in parallel rows over one and the same

fire-chamber, and tightly-closed walls and crown, whereby all the air for combustion is supplied through the ash-pit, substantially as described.

5 7. A furnace provided with a suitable grate, a series of charging-holes in the crown, arranged in parallel rows, in combination with a receptacle for containing fuel and supplying it directly to said charging-holes, substantially as described.

8. A furnace provided with a suitable grate, a series of charging-holes in the crown, arranged in parallel rows, in combination with a receptacle placed on top of the furnace be-

tween the charging-holes, and having discharge-openings opposite to the respective charging-holes, substantially as described.

9. A furnace having a suitable grate, and a series of charging-holes in the crown arranged in parallel rows over one and the same fire-chamber, in combination with a combustion-chamber between the fire-chamber and the point where the heat is applied, substantially as described.

LEMAN P. RIDER.
